UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 14,019, dated July 3, 1883.

Application filed May 16, 1883. Term of patent 3½ years.

To all whom it may concern:

Be it known that I, ARTHUR L. HALLIDAY, of New York, in the county and State of New York, have invented a new and original Design 5 for Carpets, of which the following is a specification.

The accompanying photograph illustrates my new design for carpet.

This invention relates to a new design for 10 carpets, oil-cloths, and analogous fabrics; and it consists of the new ornamentation of parts hereinafter more fully pointed out.

A band, *p*, which contains a series of rectangular figures, divides the carpet into an upper stripe or portion, *A*, and a lower stripe or portion, *B*. The upper portion, *A*, contains representations of fanciful flowers *a a*, that appear to be supported on straight stems having leaves *b*, some of these stems being longer and some shorter, as shown. The stems 15 of the flowers project from the band *p*. On this band is also the representation *d* of part of a sunflower. The lower portion, *B*, of the carpet has a series of rosettes, *e e*, ranged in

various groups, and between these groups of 25 rosettes is a floral branch, *f*, bearing circular flowers with radiating outer circumferences. At each side of the spray or figure *f* is a fanciful flower, *g*, of peculiar outline, the stem of which has leaves *h*. Adjoining each flower 30 *g* is a still taller flower, *i*, of fanciful form, reaching up nearly to the band *p*, and placed on a straight stem having leaves *j*.

I claim—

1. The design for carpets, consisting of the figures *a b d*, substantially as shown.
2. The design for carpets, consisting of the figures *a b d p*, substantially as shown.
3. The design for carpets, consisting of the figures *e f g h i j*, and *p*, substantially as 40 shown.
4. The design for carpets, consisting of the figures *a b d p e f g h i j*, substantially as shown.

ARTHUR L. HALLIDAY.
